(57) **CLAIM**

The ornamental design for a bottle holder, as shown and described.

DESCRIPTION

In a preferred embodiment, the nature of this product is a holder for a bottle suitable to be mounted in a bathing area. In a most preferred form the holder also dispenses fluid from the bottle in an automated fashion.

FIG. 1 is a top, left, front perspective view of a bottle holder embodying our new design;

FIG. 2 is a front elevational view thereof;

FIG. 3 is a left side elevational view thereof, the right side elevational view being a mirror image of the left side shown;

FIG. 4 is a rear elevational view thereof;

FIG. 5 is a top plan view thereof; and,

FIG. 6 is a bottom plan view thereof.

The broken line representations holes in FIGS. 1 and 3-6, of a nozzle in FIGS. 1-4 and 6, of a receiving wall structure in FIGS. 1 and 3-5, of a seam in FIGS. 1-4, and of a supporting rib in FIGS. 1 and 3-6, are for the purpose of illustration only, and form no part of the claimed design.
